(57) **CLAIM**

The ornamental design for a solar street light, as shown and described.

DESCRIPTION

FIG. 1 is a perspective view of a solar street light design showing the first embodiment of our new design.

FIG. 2 is a front view of a solar street light.

FIG. 3 is a rear view of a solar street light.

FIG. 4 is a left side view of a solar street light.

FIG. 5 is a right side view of a solar street light.

FIG. 6 is a top view of a solar street light.

FIG. 7 is a bottom view of a solar street light.

FIG. 8 is a second embodiment of FIG. 1; and,

FIG. 9 is a third embodiment of FIG. 1.

FIGS. 8 and 9 are alternate embodiments of FIG. 1, the only difference being the configuration of the front view, it being understood that all other surfaces not shown are the same as those of the first embodiment, and the right side views being mirror images of the left side views disclosed.

The broken lines in the drawings depict portions of the solar street light that form no part of the claimed design.
